RHEOSTAT WITH CENTRIFUGAL OPERATOR

Robert A. Felburg, Newark, N. J.

Application April 23, 1946, Serial No. 664,166

10 Claims. (Cl. 201—48)

1

My invention relates broadly to control means for electrical apparatus and more particularly to a centrifugal governing mechanism for rotating electrical apparatus.

This application is a continuation-in-part of my application Serial No. 501,472, filed September 7, 1943, now Patent No. 2,399,218, issued April 30, 1946, for Aircraft landing gear.

One of the objects of my invention is to provide a construction of centrifugal operating control mechanism for rotating electrical apparatus.

Another object of my invention is to provide an arrangement of centrifugal weights associated with the rotary element of an electrical motor or generator for controlling an electrical contact system according to the speed of the motor or generator for correspondingly controlling the electrical circuit associated with the motor or generator.

Still another object of my invention is to provide a compact arrangement of an electrical circuit control element associated with an electrical motor or generator which may be variably controlled according to the speed of operation of the motor or generator for correspondingly controlling the electrical circuit associated with the motor or generator.

Still another object of my invention is to provide a compact arrangement of an electrical circuit control element associated with an electrical motor or generator which may be variably controlled according to the speed of operation of the motor or generator for correspondingly controlling the electrical circuit associated with the motor or generator.

Still another object of my invention is to provide an arrangement of circuit control elements concentrically associated with the operating shaft of rotating electrical apparatus and which includes a calibrated resistance progressively tapped and controlled by centrifugal mechanism for associating the resistance in circuit with the rotating electrical apparatus as a starting resistance, as a constant speed governor, or as a starter governor combination in the control circuit of the apparatus.

Other and further objects of my invention reside in the construction of a compactly arranged centrifugally operated control mechanism for rotating electrical machinery in general, as set forth more fully in the specification hereinafter following by reference to the accompanying drawings, in which:

Figure 1 is a vertical sectional view taken through an electric motor or generator equipped

with the centrifugally operated electrically controlled mechanism of my invention; Fig. 2 is a transverse sectional view taken substantially on line 2—2 of Fig. 1; Fig. 3 is a perspective view of a fragmentary portion of the variable electrical contact system employed in the control system of my invention; Fig. 4 is an enlarged fragmentary transverse sectional view taken through the contact system employed in the control mechanism of my invention; Fig. 5 is a schematic view illustrating the calibrated resistance which is variably included in circuit with the rotating equipment during starting of the equipment; Fig. 6 is a schematic view illustrating the arrangement of resistance which is provided for the mechanism when used as a constant speed governor in rotatable electrical apparatus; Fig. 7 is a schematic view of the resistance which is associated with the rotating electrical apparatus for operation as a starter governor combination; Fig. 8 is a schematic view illustrating the position of the control resistance in circuit with the rotating electrical apparatus; Fig. 9 is a longitudinal cross sectional view taken through a modified form of control switch mechanism applied to an electric motor, the governing mechanism being shown in normal operating position and below an excessive speed condition for maintaining the contacts of the switch mechanism closed; Fig. 10 is a transverse sectional view taken on line 10—10 of Fig. 9; and Fig. 11 is a fragmentary sectional view showing the contacts of the switch mechanism separated under conditions of excessive speed of the governing mechanism.

Referring to the drawings in more detail, reference character 1 indicates a rotating electrical apparatus such as an electric motor or an electric generator having a shaft 31 which extends through a tubular member 2 projecting from the apparatus 1 and beyond the housing 53 for connection to any desired work application in the case of a motor or to a prime mover in the case on a generator. Ball races 3 are located at spaced intervals for mutually supporting the shaft 31 and tubular member 2. Tubular member 2 provides a bearing surface over which the tubular member 5 is free to longitudinally slide. The tubular member 4 is provided with a flange 5 at the end thereof which is peripherally screw-threaded at 5a for receiving coacting internal screw threads on coupling member 6 which terminates in a flanged wall 7 having a central aperture 7a therein for the passage of the slidably adjustable sleeve 81. The slidably adjustable sleeve 81 terminates in an annular flange 84

which establishes low friction coupling relation with the coupling member 6 through ball bearing recess indicated at 8 and 9. Thus, flange 84 may be rotatably driven at high speed and displaced longitudinally along shaft 31 proportional to speed for imparting translatory movement of the brush contact 10 insulatingly and resiliently supported through insulator 11 and spring member 12 on slidable tubular member 4.

The electrical brush member 10 slides over a multiplicity of longitudinally arranged contact members represented generally at 14, suspended by a channel member 14a depending from the coil support 15. The contact members 14 are suspended in a row longitudinally of the annular coil-supporting frame 15 which compactly surrounds the slidable tubular member 4, the tubular member 2 and the rotatable shaft 31. The annular coil support 15 is wound with resistance wire represented generally at 16 and which is provided with a multiplicity of progressive taps, which I have represented variously in Figs. 1-7 as graduated from 0-20 depending upon the type of control to be impressed upon the circuit through the apparatus.

The position of the brush or movable contact 10 is controlled by the movement of the centrifugal weights 73 and 74 attached to arms 71 and 72, respectively, and pivotally secured at 69 and 70 to the sleeve 61, which sleeve is set in a selected position on rotatable shaft 31 by means of set screw 68. The arms 71 and 72 connect through links 77 and 78 pivoted at 75 and 76 to arms 71 and 72, respectively, at one end, and pivoted at 79 and 80 to sleeve 81 at the other end. Spring members 21 and 22 are associated with each of the pivotal connections 75 and 76, respectively, for continuously urging the governor arms 71 and 72 to a position relatively compressed or flush with the shaft 31 when the mechanism is at rest. The centrifugal weights 73 and 74, when spun around by rotation of shaft 31, overcomes the action of springs 21 and 22 and tend to slide the sleeve 81 to the right in viewing Fig. 1, thereby shifting brush 10 along the row of contacts 14. In order to control the movement of sleeve 81, in the case of the starter and starter-governor combination, I provide a spring member 23 mounted on shaft 31 immediately below recess 24 in shaft 31 and adjacent a recess 25 into which spring member 23 is adapted to be compressed or displaced. The spring has a contour which slopes gradually, enabling the shaped projection 82, which is carried by the slidable sleeve 81, to readily travel over the spring when the shaft 31 is accelerating.

However, when the shaft 31 is decelerating, and slide 81 is returning to a more remote left-hand position (Fig. 1) the slide projection 82 strikes the spring 23 at a very great angle. Therefore, the spring 23 tends to obstruct the slide projection 82 from passing until the current is turned off and the spring pressure of the governor overcomes the weaker spring 23.

I have shown the control circuit connected to the control winding through external connections 28 and 27 which pass through insulated bushings 26a and 27a in housing 53. Sufficient slack is maintained in cable 27 to allow slidable tube 4 to be readily displaced to its opposite limits of travel, whereby, brush or contactor 10 is enabled to establish slidable connection with the contact members 14 throughout the entire length of the path of travel of brush 10. Where desirable, a double row of contacts may be provided and ad-

ditional coating brushes mounted on slidable tube 4 for selective connection therewith. I have shown cable conductor 27 connected through flexible connection 27b to the brush 10 in insulated relation to the supporting tubular slide 4.

Where the system of my invention is applied to a motor starter, as schematically represented in Figs. 1 and 5, I may arrange the taps on resistance 16, as represented in Fig. 5 at 0', 2', 4', 6', 8', 10', 12', 14', 16', 18', and 20'. Tap 0' is connected to a limit stop 28 with which brush 10 may form a contacting abutment when all of the resistance is effectively out of the starter circuit. The taps are graduated to represent resistance in ohms in the starter circuit.

If the motor armature at a standstill were connected directly to the power mains then, since its resistance is small, a large current would flow through the armature and burn the windings and the brushes. Consequently, a resistance is inserted into the circuit when starting and gradually cut out until the motor is running at normal speed. However, the tendency in the operation of electrical machinery is to make the starters and controllers self-governing so that the machinery cannot be injured by careless or unskilled operators. The starting system herein described is very practical. The mechanism of my invention has the desirable characteristic of automatically returning to the position of high resistance should the circuit be interrupted.

Fig. 6 shows the resistance coil reversed so as to serve as a constant speed governor. Constant speed governors are necessary to maintain a desired speed, to keep electrical machinery from running away and to keep a constant speed in spite of variable loads. Fig. 7 shows the starter and constant speed governor combined to form a starter-governor combination. This combination can be used where it is desirable to automatically start electrical machinery safely and keep said machinery at a constant speed in spite of variable loads.

The resistance 16 is controlled by variable tap 10 and disposed in the motor or generator circuit in series with the brushes of armature 28 as generally indicated in Fig. 8.

The taps on resistance 16, in the constant speed governor control system of Fig. 6, are arranged in the reverse order to that illustrated in Fig. 5; that is taps 0'', 1'', 2'', 3'', 4'', 5'', 6'', 7'', 8'', 9'', and 10'' and movement of brush 10 toward the right tends to cut in the effective resistance.

In the starter governor combination shown in Fig. 7, the taps are arranged from a low resistance intermediate position along resistance 16 as represented at 29 to a high resistance value progressing on opposite sides thereof, as represented by taps extending to the right of the intermediate point 29 at 2''', 4''', 6''', 8''', and 10'''. A similar arrangement of graduated resistance extending from a relatively low value to a relatively high value is arranged on the left of intermediate tap 29 as represented at 2''', 4''', 6''', 8''', 12''', 14''', 16''', 18''', and 20'''.

In the operation of the control system of my invention the revolving centrifugal governor pulls the non-revolving slide 4 out as the shaft 31 gains speed. Brush 10, mounted on insulated member 11, slides along separated contact points 14. Negative lead 27 connects with brush 10. In the case of the starter, the positive lead connects to the right end of the coil. In the case of the constant speed governor, the positive lead is connected to the left end of the coil as shown in Fig.

6. As Fig. 7 shows the positive lead is connected to the center of the coil in the case of the starter-governor combination, and the resistance increases towards each end.

Fig. 1 shows the coil in cross-section. The insulated resistance wire can be seen wound on the core at 16. At 2', 4', 6'—20' it can be seen where the resistance wire is tapped at intervals of equal resistance and connected to contact points 14 which are insulated from each other. Each contact point has the shape of a perfect cube.

The centrifugal governor has been shown in Fig. 1 in the extended position at starting with the brush 10 contacting the resistance coil 16 adjacent the end of the greatest resistance.

As the current enters the armature 28, the motor starts with a minimum amount of current allowed to flow. As the shaft 31 gains speed the centrifugal governor spins outward and the brush 10 is pulled along the contact points of decreased resistance. Therefore, the flow of current increases as the speed increases. This smooth regulation of current is not subject to the human error possible in hand starting.

Eventually the brush hits the limit stop 28, the resistance is completely cut out of the circuit and the motor (or generator) is safely running at top speed. When the motor is turned off, the weights 73 and 74 of the centrifugal governor come to rest against the shaft due to spring tension 21 and 22 and the brush is again contacting the coil at the position of highest resistance ready for starting again.

Fig. 6 shows how, by simply reversing the resistance coil, the apparatus becomes a constant speed governor. The governor may be adjusted to maintain a constant speed when the brush contacts the resistance at two ohms. Should the motor (or generator) speed up, the brush will slide along to a higher resistance. As current varies inversely with resistance, the more resistance in a circuit the less current will flow. When the motor receives less current, the brush will move down towards two ohms again and settle at a position where a balance is maintained.

If the load on the motor is increased, the motor will slow down, the brush will move towards the zero resistance, the current will increase, the motor will speed up again and tend to create a balance between load and current, thus maintaining nearly constant speed despite variable loads. Spring member 23 is not used for the constant speed governor.

Fig. 7 shows how, by winding both coils on the one core the mechanism can be used as an automatic starter and a constant speed governor. Instead of two coils, just the starter coil could be used provided double taps were taken from each point on the coil and the two high resistance wires would be tapped at either end of the row of contacts and the lesser resistance wires would progressively be placed inboard of each of the end taps until the no resistance tap would be placed in the center. When the current is turned on, the brush slides over the resistance coil until all the resistance is cut out of the circuit and the motor is safely running at normal speed. It continues to gain momentum until the system balances, possibly at four ohms resistance on the governor coil. This condition will be stable until the load is decreased or increased. If the load is decreased, the centrifugal governor will pull the brush up to a higher resistance where it

will balance and stay constant for that load. Should the load increase, then the brush 10 will slide down towards the zero resistance, more current will enter the circuit and the motor will balance possibly around the one ohm resistance where it will remain constant for that load. If, however, for a certain type of machinery, too great a load be added, the brush 10 will slide past the zero resistance and go on to an ever-increasing resistance. With the excess load and the diminishing current, the mechanism would have a tendency to stop the motor. Therefore, to combat such a tendency due to slight overload, spring 23 and recesses 24—25 of Fig. 1 are included in the mechanism only when the starter or starter-governor combination is used.

Slide 81 and recess 24 is standard in all forms of the switch. But when the starter or combination starter-governor is used, that shaft has the extra recess 25 and spring 23 installed. The spring 23 slopes, gradually enabling the projector 82 on slide 81 to easily travel over it when the motor is speeding up. But coming back, the slide hits the spring at a very great angle. Therefore, the spring 23 will prevent the projection 82 on slide 81 from passing until the current is turned off and the spring pressure of the governor overcomes the weaker spring 23. As a result, should the starter-governor combination shown in Fig. 7 become overloaded, the centrifugal governor will slow down and push the brush 10 along the contact points until the zero resistance is arrived at. At this point, the spring 23 will prevent the governor from pushing the brush 23 past the critical point. The slide 81 will finally push spring 23 down and slide the brush 10 to the high resistance only when the circuit is interrupted and the governor weights 73 and 74 come down against the shaft 31.

40. The constant speed governor and starter-governor combination will maintain a constant speed when there is no change in the load. In cases where there is a variable load, the governor will maintain a constant speed after it balances for that particular load. The motor will lose speed when the load is increased, but it will only lose about half the speed that a motor without the governor would lose. This is caused by the fact that the current increases as the load increases, and the current decreases as the load decreases.

45. Referring to Figs. 9-11, the motor shaft 31, which extends from the electric motor 27, carries the friction drive wheel 38 for engagement with any mechanism that is to be rotatably driven. The shaft extends through a housing 53 having an anti-friction bearing connection with shaft 31 as represented at 66. The housing 53 thus serves as a dust and moisture-tight cover for the precision mechanism contained therein.

50. The speed governing mechanism includes a sleeve member 67, secured by set screw 68 to a selected position on shaft 31. The position of sleeve 67 may be adjusted longitudinally of the shaft for increasing or decreasing the speed at which the governor mechanism operates to open the series circuit to the driving motor mechanism. Sleeve 67 is provided with pairs of radially projecting lugs represented at 69 and 70, forming pivot means for arms 71 and 72 which carry centrifugally operated weights 73 and 74 on the ends thereof. Arms 71 and 72 have lugs 75 and 76 extending inwardly therefrom forming pivotal connections for link members 77 and 78 which pivotally connect with radially extending lugs 79 and 80, carried by longitudinally slidable sleeve

member 81. The longitudinally slidable sleeve member 81 has an inwardly projecting key 82 thereon, which is longitudinally slidable in a keyway or slot 83 formed in shaft 31. As the weights 73 and 74 swing outwardly under centrifugal force due to increased speed of shaft 31 and friction drive wheel 30 in frictional engagement with the rotary member to be driven, a pull is exerted on sleeve 81 displacing sleeve 81 longitudinally of shaft 31. Sleeve 81 cannot turn relatively to shaft 31 but is only slidable longitudinally with respect thereto. The sleeve 81 has a radially extending flange 84 on the end thereof opposite to the end at which links 77 and 78 pivotally connect. The faces of flange 84 provide slidable connection with collar member 85 through the ball races indicated at 86 and 87 secured in ball race plates 88 and 89. The collar member 85 has a pair of longitudinally extending arms 90 and 91 with hook-shaped ends 90a and 91a for engagement with the inwardly extending flange 92 of collar member 93. Collar member 93 has an annular space therein indicated at 93a, within which the hook-shaped ends 90a and 91a of members 90 and 91 are free to be displaced longitudinally within definite limits. Thus a lost motion connection is provided between collar member 93 and the system of centrifugal weights including weights 73 and 74.

Sleeve member 94 projects from the housing of the motor 27 and terminates shortly beyond the closed circuit position for the governing mechanism and serves as a support and guide for the parts to which the collar assembly 93 is connected. The extremity of the sleeve 94 is grooved at 90b and 91b to allow the longitudinal movement of the arms 90 and 91 under centrifugal action of the switch control mechanism. Anti-friction bearings 95 and 96 are provided between shaft 31 and sleeve member 94 for maintaining accurate alignment of the parts and reducing friction to a minimum.

The collar assembly 93 has an insulated bushing 97 and a ring member 98 secured thereto by screw members 99. Insulated bushing 97 slidably connects with sleeve member 94 and may be displaced longitudinally thereof. The insulated bushing 97 serves as an insulated support for the annular conductive ring member 100. The securing screws 99 are countersunk in insulated bushing 97 and thus do not electrically connect with ring member 100. The ring member 100 is provided with an inwardly extending flange 100a fitting within an annular groove in insulated bushing 97 for forming a substantial mechanical connection therewith while at the same time maintaining ring member 100 in substantial insulated relation to all parts of the collar assembly 93. There is embedded in insulated bushing 97 an eyelet member 101 in insulated relation to ring member 100, ring member 98 and the other parts of the collar assembly 93. The eyelet 101 provides a connection for coil spring 102 which is secured at the other end 103 to the frame of the motor 27. Coil spring 102 tends to continuously draw the collar assembly 93 toward the motor frame 27 for maintaining the face of conductive annular ring 100 in electrical connection with the contact segments 104 and 105 forming the terminals for the series circuit through conductors 52 and 54 in the series control path explained in Fig. 8. The segments 104 and 105 are insulatingly mounted as represented at 106 and 107 in the extremity of the tubular frame member 108 that projects from the motor frame

27. The conductors 52 and 54 enter opposed sides of housing 53 through insulated bushings 108 and 110 as shown and electrically connect with segments 105 and 104.

5 Under normal conditions of rotation, coil spring 102 maintains the annular conductive ring 100 in contact with the segments 104 and 105. However, as the speed increases, the centrifugal weights move outwardly, displacing sleeve 81 longitudinally of the shaft system until a position is reached in which the hook-shaped ends 90a and 91a of arms 90 and 91 pull the collar assembly 93 further away from the end of tubular member 108, as represented in Fig. 11, separating the annular conductive ring member 100 from electric circuit connection with segments 104 and 105, thus opening the series circuit path illustrated as closed in the position shown in Fig. 9.

20 The arrangement of the apparatus of my invention shown in Figs. 1-8 is intended for the control of a circuit variable in association with any rotating electrical apparatus, whereas, in the form of my invention illustrated in Figs. 9-11, I have shown a mechanism for positively interrupting the continuity of an electrical circuit associated with the rotating electrical apparatus. Depending upon the conditions under which the apparatus must operate, one or the other of the alternative arrangements may be very effectively employed.

25 I realize that various changes may be made in the construction of the components of the centrifugal switch system of my invention and, while 35 I have described my invention in certain of its preferred embodiments, I desire that it be understood that no limitations upon my invention are intended other than are imposed by the scope of the appended claims.

30 40 What I claim as new and desire to secure by Letters Patent of the United States is as follows:

1. A centrifugal control switch for electric motors comprising a driven motor shaft, a centrifugal weight system displaceable in proportion to the speed of the motor shaft, a tubular projection 45 concentrically surrounding said motor shaft and forming a guide, a collar member slidable on the guide formed by said tubular projection, a connection between said centrifugal weights and said collar member, an electric contact system associated with said collar member, a complementary electric contact system associated with said tubular projection, and spring means for normally maintaining said contact systems in electrical contact for completing an electrical circuit through said contact systems, said centrifugal weights operating under conditions of excessive speed for separating said contact systems and opening the electrical circuit.

50 60 2. A centrifugal control switch comprising in combination with a driven shaft, a tubular member surrounding said shaft in spaced relation thereto, a displaceable tube mounted for longitudinal sliding movement on said tubular member, an electrical contactor supported by said displaceable tube, an impedance surrounding said displaceable tube and having a multiplicity of progressively arranged contacts connected with spaced taps therein, said contacts being engageable by said electrical contactor supported by said displaceable tube, and means fixed to said driven shaft for varying the position of said displaceable tube and electrical contactor carried thereby according to the speed of rotation of said driven shaft.

3. A centrifugal control switch comprising in combination with a driven shaft, a tubular member surrounding said shaft in spaced relation thereto, a displaceable tube mounted for longitudinal sliding movement on said tubular member, an electrical contactor supported by said tube, an impedance surrounding said displaceable tube and having a multiplicity of progressively arranged contacts connected with spaced taps therein, said contacts being engageable by said electrical contactor supported by said displaceable tube, means fixed to said driven shaft for varying the position of said displaceable tube and electrical contactor carried thereby according to the speed of rotation of said driven shaft, and means associated with said driven shaft for restricting the movement of said displaceable tube and the displacement of said electrical contactor with respect to said progressively arranged contacts.

4. A centrifugal switch comprising in combination with a driven shaft, a tubular housing surrounding said shaft, a frame structure disposed in concentric spacial relation to said tubular housing, a winding carried by said frame structure, progressively disposed taps on said impedance winding, a row of progressively arranged contacts mounted in insulated relation to said frame structure and intermediate said frame structure and said tubular housing, connections progressively arranged between said contacts and the taps on said winding, a slideable electrical contactor movable between said housing and said progressively arranged row of contacts for establishing progressive electrical connection therewith, and means associated with said driven shaft for variably displacing said slideable electrical contactor in accordance with the velocity of rotation of said driven shaft for variably including an effective portion of said impedance winding in an electrical circuit between said electrical contactor and one terminating end of said impedance winding in proportion to the speed of rotation of said driven shaft.

5. A centrifugal switch comprising in combination with a driven shaft, a tubular housing surrounding said shaft in spaced relation thereto, a frame structure disposed in concentric spacial relation to said tubular housing, a winding carried by said frame structure, progressively disposed taps on said impedance winding, a row of progressively arranged contacts mounted in insulated relation to said frame structure and intermediate said frame structure and said housing, connections progressively arranged between said contacts and the taps on said winding, a tubular member slideable on said tubular housing within said frame structure, an electrical contactor mounted on said tubular member and movable between said tubular housing and said progressively arranged rows of contacts for establishing progressive electrical connection therewith, a centrifugally operated mechanism associated with said driven shaft and coupling means between said centrifugally operated mechanism and said tubular member for progressively displacing said electrical contactor with respect to said progressive row of contacts in proportion to the speed of rotation of said driven shaft for effectively including a selected portion of said impedance winding in a series circuit between said electrical contactor and one of the terminating ends of said impedance winding in proportion to the speed of rotation of said driven shaft.

6. A centrifugal switch comprising in combi-

10
nation with a driven shaft, a tubular housing surrounding said shaft in spaced relation thereto, a frame structure disposed in concentric spacial relation to said tubular housing, an impedance winding carried by said frame structure, progressively disposed taps on said impedance winding, a row of progressively arranged contacts mounted in insulated relation to said frame structure and intermediate said frame structure and said housing, connections progressively arranged between said contact and the taps on said impedance winding, a tubular member slideable on said tubular housing within said frame structure, an electrical contactor mounted on said tubular member and movable between said tubular housing and said progressively arranged row of contacts for establishing progressive electrical connection therewith, a centrifugally operated mechanism associated with said driven shaft, coupling means between said centrifugally operated mechanism and said tubular member for progressively displacing said electrical contactor with respect to said progressive row of contacts in proportion to the speed of rotation of said driven shaft for effectively including a selected portion of said impedance winding in a series circuit between said electrical contactor and one of the terminating ends of said impedance winding in proportion to the speed of rotation of said driven shaft, and spring means associated with said centrifugal means for normally biasing said electrical contactor to a predetermined limiting position with respect to said progressive row of contacts.

7. A centrifugal switch comprising in combination with a driven shaft, a tubular housing surrounding said shaft in spaced relation thereto, a frame structure disposed in concentric spacial relation to said tubular housing, a winding carried by said frame structure, progressively disposed taps on said impedance winding, a row of progressively arranged contacts mounted in insulated relation to said frame structure and intermediate said frame structure and said housing, connections progressively arranged between said contact and the taps on said impedance winding, a tubular member slideable on said tubular housing within said frame structure, an electrical contactor mounted on said tubular member and movable between said housing and said progressively arranged row of contacts for establishing progressive electrical connection therewith, a centrifugally operated mechanism associated with said driven shaft and anti-friction rotative coupling means between said centrifugally operated mechanism and said tubular member for progressively displacing said electrical contactor with respect to said progressive row of contacts in proportion to the speed of rotation of said driven shaft for effectively including a selected portion of said impedance winding in a series circuit between said electrical contactor and one of the terminating ends of said impedance winding in proportion to the speed of rotation of said driven shaft, spring means associated with said centrifugal means for normally biasing said electrical contactor to a predetermined limiting position with respect to said progressive row of contacts, and means associated with said driven shaft and engageable with a portion of said anti-friction rotative coupling means for restricting longitudinal displacement of said anti-friction rotative coupling means with respect to said shaft in coaction with the operation of said centrifugal means.

8. A centrifugal control switch comprising in

combination with a driven shaft, a tubular member surrounding said shaft in spaced relation thereto, a displaceable tube mounted for longitudinal sliding movement on said tubular member, an electrical contactor supported by said displaceable tube, an annular flange on one end of said displaceable tube, a coupling member slideable on said shaft and having a flange adapted to coact with and extend substantially parallel to the aforesaid flange, means coupling said flanges one to the other while allowing free rotative movement of said last mentioned flange with respect to said first mentioned flange, an impedance surrounding said displaceable tube and having a multiplicity of progressively arranged contacts connected with spaced taps therein, said contacts being engageable by said electrical contactor supported by said displaceable tube, and means fixed to said driven shaft and connected with said coupling member for imparting translatory movement to said coupling member for varying the position of said displaceable tube and the electrical contactor carried thereby according to the speed of rotation of said driven shaft.

9. A centrifugal control switch comprising in combination with a driven shaft, a tubular member surrounding said shaft in spaced relation thereto, a displaceable tube mounted for longitudinal sliding movement on said tubular member, an electrical contactor supported by said displaceable tube, an annular flange on one end of said displaceable tube, a coupling member slideable on said shaft and having a flange adapted to coact with and extend substantially parallel to the aforesaid flange, means coupling said flanges one to the other while allowing free rotative movement of said last mentioned flange with respect to said first mentioned flange, an impedance surrounding said displaceable tube and having a multiplicity of progressively arranged contacts connected with spaced taps therein, said contacts being engageable by said electrical contactor supported by said displaceable tube, and means fixed to said driven shaft and connected with said coupling member for imparting translatory movement to said coupling member for varying the position of said displaceable tube and the electrical contactor carried thereby according to the speed of rotation of said driven shaft, and means

extending between said coupling member and said shaft for limiting the movement of said displaceable tube in opposite directions.

10. A centrifugal control switch comprising in combination with a driven shaft, a tubular member surrounding said shaft in spaced relation thereto, a displaceable tube mounted for longitudinal sliding movement on said tubular member, an electrical contactor supported by said displaceable tube, an annular flange on one end of said displaceable tube, a coupling member slideable on said shaft and having a flange adapted to coact with and extend substantially parallel to the aforesaid flange, a sleeve member having a cylindrical portion connected with said first mentioned flange and embracing said second mentioned flange and terminating in a flange member extending in spaced parallel relation to said second mentioned flange, ball races interposed between the opposite faces of said second mentioned flange and the face of said first mentioned flange and the face of said flange member, anti-friction ball members disposed in said ball races, an impedance surrounding said displaceable tube and having a multiplicity of progressively arranged contacts connected with spaced taps therein, said contacts being engageable by said electrical contactor supported by said displaceable tube, and means fixed to said driven shaft and connected with said coupling member through said second mentioned flange and the ball race connections thereof with said first mentioned flange and the flange member of said sleeve for imparting translatory movement to said coupling member for varying the position of said displaceable tube and the electrical contactor carried thereby according to the speed of rotation of said driven shaft.
